DESIGN FOR A DISPLAY MEDALLION OR SIMILAR ARTICLE

Benjamin Puciloski, Cicero, Ill.

Application April 9, 1937, Serial No. 68,649

Term of patent 14 years

To all whom it may concern:

Be it known that I, Benjamin Puciloski, a citizen of the United States, and residing in the town of Cicero, in the county of Cook and State of Illinois, have invented a new, original, and ornamental Design for a Display Medallion or Similar Article, of which the following is the specification, reference being had to the accompanying drawing, forming a part thereof.

On the drawing:

Fig. 1 is a front elevational view of a medallion showing my new design.

Fig. 2 is a side elevational view thereof on a reduced scale.

I claim:

The ornamental design for a display medallion or similar article, substantially as shown and described.

BENJAMIN PUCILOSKI.
